(57) **CLAIM**

The ornamental design for an air compressor, as shown and described.

DESCRIPTION

FIG. 1 is a perspective view of an air compressor showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of a variation of the air compressor.

The evenly-dotted broken lines depict portions of an air compressor in which the design is embodied that form no part of the claimed design.

The dash-dotted broken lines are for defining the bounds of the claimed design only and form no part of the claimed design.

1 Claim, 8 Drawing Sheets(56)
